UNITED STATES PATENT OFFICE

WILLIAM H. BENEDICT, OF COSCOB, CONNECTICUT, ASSIGNOR TO CHICAGO PNEUMATIC
TOOL COMPANY, OF NEW YORK, N. Y., A CORPORATION OF NEW JERSEY

PORTABLE PERCUSSIVE TOOL

Application filed April 5, 1928. Serial No. 267,624.

This invention relates to portable power operated percussive tools adapted to be manually supported and directed to the work. It has practical application to tools for hand 5 drilling and demolition work generally.

One object of the invention is to provide improved means for relieving the operator of the shock and reaction of the tool when in operation. Another object is to protect the 10 tool against the destructive effects of vibration. Another object is to support and to control the operation of the percussive motor of such a tool in an improved manner. Other objects will be apparent from the detailed 15 description which follows:

In order to illustrate the invention one concrete embodiment thereof is shown in the accompanying drawings in which:

Fig. 1 is a vertical sectional view showing 20 a portion of the percussive motor in elevation, the latter being in its retracted or non-operative position; and

Fig. 2 is a view similar to Fig. 1 showing the motor in running position.

The invention comprises a member 3 generally cylindrical in form providing an elongate chamber 3a in which is slidably mounted a percussive motor A adapted to impart its blows to a drill steel or other working tool 25 B which extends into the forward or barrel end of motor A. Cylinder member 3 is arranged to be manually supported and controlled by one or more handles 4, which may be integral with or secured to member 3. In 30 the present instance the handles form portions of a T head or rearward extension 5 secured to member 3 in any suitable manner as by bolts (not shown). Backhead 5 is hollow and forms a portion of the chamber 3a in which motor A moves, a bearing ring 6 and suitable packing means being provided between backhead 5 and cylinder 3 for a purpose presently to be described. The admission 35 of pressure fluid through an inlet 7 in backhead 5 is controlled by a suitable throttle valve 8 operated by a lever 9 adjacent handles 4, the fluid passing valve 8 being arranged to enter the rearward or handle portion of chamber 3a.

Motor A has a head 10 slidably fitting the

central portion of chamber 3a, a rearward extension 11 which telescopes within the hollow backhead 5 and has a fluid tight bearing in ring 6, and a barrel extension 12 which projects through and beyond the open end of member 3 and receives the shank end of the working tool B. A fluid-tight bearing and packing arrangement is provided at the outer end of member 3 comprising packing ring 13, packing 14 and gland nut 15. Head 10 55 has suitable packing means at 16 and controls one or more radial ports 17 extending through the wall of cylinder member 3. The rearward portion of head 10 is reduced in diameter and communicates freely with the space between 60 the head 10 and bearing ring 6.

Motor A and supporting cylinder 3 co-operate to divide the elongate chamber 3a of the latter into three distinct parts or chambers, which vary in size with the movement 70 of motor A. The three parts comprise the live air port or chamber rearwardly of bearing ring 6 and into which motor extension 11 extends, the intermediate or exhaust chamber between the head 10 and bearing ring 6 which 75 communicates with atmosphere through ports 17 when the motor moves to the position shown in Fig. 2, and the cushion chamber provided between motor head 10 and packing ring 13. The opposed pressure areas of 80 motor A provided by extension 11 (which is subjected to pressure in the live air chamber) on the one hand and by the forward face of head 10 on the other (which is subjected to the pressure in the cushion chamber) are differential in size, the area presented by extension 11 being somewhat the larger so that when throttle valve 8 is open the pressure of the admitted motive fluid operates to move 85 motor A forwardly. Extension 11 has an axial bore as indicated which serves to conduct a portion of the pressure fluid in the live air chamber to the percussive motor to operate the same.

Motor A may be of any suitable or desired type. As shown, it comprises a hammer piston 18 whose reciprocations are controlled by an automatic pressure thrown sleeve valve 19 disposed in a valve box 20 provided with a lid 21, the valve parts being disposed within 90 95 100

head 10 and securely held in place by extension 11. The exhaust of the motor is discharged into the annular chamber produced by the reduced rearward portion of head 10.

In order to cushion the forward movement of motor A and to return the motor to its rearward or inoperative position (Fig. 1), means are provided for admitting a charge of pressure fluid to the cushion chamber provided between head 10 and packing ring 13. By preference one charge is admitted to the cushion chamber when the tool is started and another charge is directed thereto when the tool is stopped, there being no supply of fluid to the cushion chamber while the tool continues in operation. The preferred arrangement includes a passage 22 in cylinder 3 which opens into the cushion chamber on the one hand through a port 22a and terminates in a port 22b adjacent the fluid pressure inlet of the tool. Port 22b is controlled by the head of a plunger 23 which by preference takes the form of an extension on throttle valve 8. Adjacent the head of extension or plunger 23 is an annular groove 24 of sufficient width to admit a charge of pressure fluid to passage 22 when the throttle valve moves from the closed position shown in Fig. 1 to the open position shown in Fig. 2, and another charge when the throttle valve moves back to closed position. In either the fully closed or fully opened position of the valve, port 22b is cut off by plunger 23 from communication with the motive fluid inlet. Accordingly, when the operator actuates lever 9 to open throttle valve 8, a charge of pressure fluid goes through passage 22 to the cushion chamber, which charge is compressed by the forward movement of motor A due to the proportionately greater area of extension 11 which is subjected to the live motive fluid. The forward movement of motor A continues until the effective pressure in the live air chamber is equalized by the effective pressure in the cushion chamber. Motor A goes into operation as soon as the advancing movement of the motor places ports 17 in communication with the exhaust portion of chamber 3a (Fig. 2). The running position of motor A in cylinder 3 is determined to a certain extent by the pressure applied by the operator to handles 4, which pressure assists the effective pressure in the cushion chamber in balancing the preponderating pressure which tends to move the motor forwardly in cylinder 3. When the operator closes the throttle valve a second charge of fluid is admitted to the cushion chamber, as previously described, and the pressure therein operates to move motor A rearwardly as the pressure in the live air chamber escapes through the motor to the exhaust chamber and thence to atmosphere through ports 17, the rearward movement of the motor continuing until the ports 17 are closed off by head 10 whereupon the

motor comes to rest in the position shown in Fig. 1.

The working tool B is arranged to be retained in operative relation with percussive motor A without interfering with the movement of the motor in cylinder 3, the retaining means being connected to a rigid portion of the tool so that the operator can conveniently withdraw the tool and shift it to a new location. To secure a rigid connection and yet to permit the use of a retainer of minimum length, gland nut 15 is provided with an enlarged extension 15a, which encloses and protects the projecting end of motor A when the latter is in its retracted or inoperative position (Fig. 1). The retainer is secured to the extension 15a and in the present instance is in the form of a yoke 25, which cooperates with the collar b on the shank of the working tool. Yoke 25 has inturned ends 25a extending into suitable sockets in extension 15a, this pivotal connection enabling the retainer to be swung to one side when the working tool B is to be removed or inserted in the tool.

While a preferred form of the invention has been herein shown and described, it is to be understood that the invention is not limited to the specific details thereof, but covers all changes, modifications and adaptations within the scope of the appended claims.

I claim as my invention:

1. A fluid pressure tool comprising a member providing an elongate chamber, a handle on said member for manually supporting the latter, a fluid pressure percussive motor movable as a unit in said chamber, and means on said member and said motor cooperating to provide opposing pressure chambers and an intermediate exhaust chamber, and means for trapping pressure fluid in one of said pressure chambers.

2. A fluid pressure tool comprising a member providing an elongate chamber with an open end, a handle on said member for manually supporting the latter, means for restricting a portion of said chamber remote from said open end, and a percussive motor movable as a unit in said chamber and having a part projecting through said open end and an extension in said restricted portion.

3. A fluid pressure tool comprising a member providing an elongate chamber open at one end and closed at the other, a handle on said member for manually supporting the latter, means for restricting a portion of said chamber adjacent the closed end of the same, a percussive motor movable as a unit in said chamber and having a part projecting through said open end and an extension in said restricted portion, said extension serving as a conduit for supplying pressure fluid to said motor.

4. A fluid pressure tool comprising a cylinder member providing an elongate cham-

ber having a closed end, a fluid pressure motor movable within said chamber, cooperating means on said member and said motor for dividing said chamber into three parts which

5 vary in size with the movement of said motor, said means including a bearing ring within said chamber in spaced relation to the closed end thereof and a head on said motor slidably fitting said chamber beyond said ring, an extension on said motor slidably fitting said bearing ring and projecting within the rearmost part of said chamber, said member having vent ports controlled by said head and arranged on forward movement of

10 15 said motor to connect the portion of the chamber between said head and said ring to atmosphere.

5. A fluid pressure tool comprising a cylinder member providing an elongate chamber having a closed end, a fluid pressure motor movable within said chamber, cooperating means on said member and said motor for dividing said chamber into three parts which vary in size with the movement of said motor, said means including a bearing ring within said chamber in spaced relation to the closed end thereof and a head on said motor slidably fitting said chamber beyond said head, an extension on said motor slidably fitting said bearing ring and projecting within the rearmost part of said chamber, said member having vent ports controlled by said head and arranged on forward movement of said motor to connect the portion of the chamber between said head and said ring to atmosphere, said motor having a barrel extending beyond said cylinder member, packing and bearing means on said cylinder for said barrel defining a cushion chamber between the same and said head, and means for supplying a charge of pressure fluid to said cushion chamber to move said motor rearwardly or to resist its forward movement.

6. A fluid pressure tool comprising a cylinder member providing an elongate chamber, a fluid pressure motor movable within said chamber, cooperating means on said member and said motor for dividing said chamber into three parts, namely, a live air chamber, an exhaust chamber, and a cushion chamber, the relative sizes of said chambers being varied by the movement of said motor, means for admitting pressure fluid to said live air chamber and for conducting a portion thereof to said motor to operate the latter, and means for supplying a charge of pressure fluid to said cushion chamber.

7. A fluid pressure tool comprising a handle member providing an elongate chamber, a fluid pressure percussive motor mounted for sliding movement in said chamber, means for controlling the position of said motor within said chamber by pressure fluid including opposed areas on said motor, and means operating automatically for directing

a charge of pressure fluid to one of said areas when the tool is started and for shutting off further supply to said area while the tool is in operation.

8. A fluid pressure tool comprising a handle member providing an elongate chamber, a fluid pressure percussive motor mounted for sliding movement in said chamber, means for controlling the position of said motor within said chamber by pressure fluid including opposed areas on said motor, and means operating automatically to direct a charge of pressure fluid to one of said areas only at the starting and stopping of said tool.

9. A fluid pressure tool comprising a handle member providing an elongate chamber, a fluid pressure percussive motor mounted for sliding movement in said chamber and having opposed areas, means for controlling the position of said motor, and means for directing a charge of pressure fluid to one of said areas when the pressure fluid is admitted to said motor to provide a resilient cushion for said motor and again, when the supply of pressure fluid is cut off, in order to move said motor to its rearmost position within said member.

10. A fluid pressure tool comprising a member providing an elongate chamber, means for controlling the admission of pressure fluid to said chamber including a throttle valve, a fluid pressure motor movably mounted in said chamber and presenting a pressure area to the admitted motive fluid and providing an opposing pressure area of small extent, and means operating automatically only when said valve is opened or closed for admitting a charge of pressure fluid to said smaller area.

11. A fluid pressure tool comprising a member providing an elongate chamber, means for controlling the admission of pressure fluid to said chamber including a throttle valve, a fluid pressure motor movably mounted in said chamber and presenting a pressure area to the admitted motive fluid and providing an opposing pressure area of small extent, and means controlled by said throttle valve for admitting a charge of pressure fluid to said smaller area momentarily during the opening movement of said valve.

12. A fluid pressure tool comprising a member providing an elongate chamber, means for controlling the admission of pressure fluid to said chamber including a throttle valve, a fluid pressure motor movably mounted in said chamber and presenting a pressure area to the admitted motive fluid and providing an opposing pressure area of smaller extent, and means associated with said throttle valve for directing pressure fluid momentarily to said smaller area at the opening and closing of said valve.

13. A fluid pressure tool comprising a member providing an elongate chamber,

means for controlling the admission of pressure fluid to said chamber including a throttle valve, a fluid pressure motor movably mounted in said chamber and presenting a pressure area to the admitted motive fluid and providing an opposing pressure area of smaller extent, and means for admitting a charge of pressure fluid to said smaller area when said throttle valve is opened, said last named means comprising an extension on said valve and a passage in said member leading to said smaller area and controlled by said extension.

14. A fluid pressure tool comprising a member providing an elongate chamber, means for controlling the admission of pressure fluid to said chamber including a throttle valve, a fluid pressure motor movably mounted in said chamber and presenting a pressure area to the admitted motive fluid and providing an opposing pressure area of smaller extent, and means associated with said throttle valve for directing pressure fluid momentarily to said smaller area at the opening and closing of said valve, said last-named means comprising a plunger having a reduced portion actuated by said valve and a passage in said member leading to said smaller area, said passage receiving pressure fluid by the reduced portion of said plunger during the movement of the latter in either direction.

15. A fluid pressure tool comprising a cylinder member having a handle and providing an elongate chamber, a fluid pressure percussive motor movable within said chamber and projecting therebeyond, packing and bearing means on said member for the projecting portion of said motor including a gland nut, a working tool extending within said motor to receive the blows thereof, and means on said gland nut for retaining said working tool in operative relation with said motor without interfering with the movement of the latter in said member.

16. A fluid pressure tool comprising a cylinder member having a handle and providing an elongate chamber, a fluid pressure percussive motor movable within said chamber and projecting therebeyond, packing and bearing means on said member for the projecting portion of said motor including a gland nut, a working tool extending within said motor to receive the blows thereof, and a retainer yoke on said gland nut for retaining said working tool in operation relative to said motor without interfering with the movement of the latter in said member.

Signed by me at Cos Cob, in the county of Fairfield and State of Connecticut, this 4th day of April, 1928.

WILLIAM H. BENEDICT.
